UNITED STATES PATENT OFFICE.

WILLIAM S. THOMAS, OF LOCK HAVEN, PENNSYLVANIA.

SPARK-PLUG.

1,325,595.

Specification of Letters Patent. Patented Dec. 23, 1919.

Application filed January 4, 1918. Serial No. 210,252.

To all whom it may concern:

Be it known that I, WILLIAM S. THOMAS, a citizen of the United States, residing at Lock Haven, in the county of Clinton and State of Pennsylvania, have invented certain new and useful Improvements in Spark-Plugs, of which the following is a specification.

My invention relates to spark plugs such as used in connection with internal combustion engines and consists particularly of auxiliary electrode insulating means which is so located and positioned as to prevent oil, gas, or the products of combustion in the engine from penetrating said insulating means, thereby increasing the efficiency of the plug, thus reducing the loss of electrical current to a minimum through insulator leakage.

20 A further object is to construct and so arrange my invention that a spark plug made in accordance therewith will be durable under the severe conditions encountered in regular use.

25 Another object is to so construct my improved spark plug that the auxiliary insulator will act as a resilient cushion between a jacket which I employ and the primary insulator for one of the electrodes.

30 A still further object of my invention is to so arrange said auxiliary insulator that it will keep the primary insulator comparatively cool.

Another object of my invention is to provide auxiliary insulating means which can be used in tight connection with a porcelain or glass insulator for a removable electrode, without breaking the glass or porcelain.

These objects, and other advantageous ends which will be described hereinafter, I attain in the following manner, reference being had to the accompanying drawings in which—

Figure 1 is an elevation, partly in section, showing a portion of a spark plug made in accordance with my invention,

Fig. 2 shows an elevation of a porcelain insulated electrode having a band of mica thereon made in accordance with my invention,

50 Fig. 3 is a transverse section taken on the line 3—3 of Fig. 1,

Fig. 4 is a sectional elevation of my improved mica band showing how the same is

made in two sections and separated from each other, and

Fig. 5 is an elevation partly in section showing an entire spark plug made in accordance with my invention and of a different form from that shown in Fig. 1.

Referring to Figs. 1 to 4, inclusive, of the drawings, 1 represents an electrode having a primary porcelain or glass insulator 2. This insulator has an enlarged portion 3 within its length, said enlarged portion having substantially flat upper and lower surfaces 4 and 5, respectively, which provide substantially parallel shoulders for a purpose hereinafter described.

An auxiliary insulating band of mica or other insulating material 6 is adapted to surround the enlarged portion 3 and this band of mica forms one of the important features of this invention. The band 6 is preferably made in two sections 7 and 8. The bottom section 8 has an inturned circular flange 9 which is adapted to engage the shoulder 5 and to surround the lower stem portion 10 of the insulator 2. The upper portion of the section 8 is reduced in diameter, as shown at 11, and a circular ledge or shoulder 12 is thus provided. The upper section 7 has a depending portion 13 which is of a diameter to snugly fit the upper edge portion of the section 8 and to abut the ledge 12 when the two sections are placed together. The section 7 also has an internal flange 14 which is adapted to surround the upper stem portion 15 of the insulator 2.

The outer diameters of the sections 7 and 8 are substantially the same so that when they are placed together the outer surfaces will be flush. The flange 14 is adapted to extend over and into engagement with the upper shoulder 4 of the enlarged portion 3 of the insulator 2. Thus the enlarged portion 3 of the insulator is housed within the band of mica 6.

The band 6 is preferably made by cutting a block of mica on a lathe or other machine and afterward this band is tightly fitted around the enlarged portion 3, in the manner as shown in Fig. 2. As illustrated in Figs. 1 and 4, the insulator with the mica band 6 is inclosed within a metallic jacket 16. This jacket includes upper and lower flanges 17 and 18, respectively, which are turned and pressed inwardly by pressure de-

vices (not illustrated), and washers 19 and 20 are interposed between the flange 17 and the section 7 of the mica band 6, and the flange 18 and the bottom of the section 8 of said mica band 6.

The jacket 16 forms an inclosure for the auxiliary insulating band 6 and serves as a seal to prevent direct contact of the products of combustion within the engine with the auxiliary band 6. Furthermore, this jacket serves as a protective means to prevent oil or carbon particles from engaging the auxiliary insulating band 6 and thereby renders the insulating properties of the band 6 extremely efficient since it is well known that if mica or similar material is impregnated with oil and carbon that it serves and acts as a conductor instead of an insulator for which it is intended.

The washer 20 is preferably made U-shape in cross section (see Fig. 1) and is preferably made of resilient metal so as to provide a tight fit between the several parts. This washer 20 is adapted to engage the bottom portion 10 of the insulator 2 and prevents any portion of the products of combustion, which may be passed between the inner edge of the flange 18 and the portion 10 of the insulator 2, from engaging the auxiliary insulating band 6. This washer 20 is preferably made of sufficiently flexible material which can firmly engage the insulator 2 without causing fracture or other injury thereto. An electrode thus housed can be placed within the body portions (not illustrated) of various types of spark plugs, such for example as the body portion of the spark plug illustrated in my application for United States patent, Serial No. 177,669.

In Fig. 5 I have illustrated the electrode insulator having the band 6 thereon and positioned directly within a body portion 21 of a spark plug, said body portion having a lower screw-threaded end 22 which can be screwed directly into an engine cylinder.

In this construction I have used flat washers 23 and 24 positioned between the top and bottom of the band 6 of the shoulder 25 of the body portion and the top flange 26 of said body portion. In all other respects the construction is similar to that described in Figs. 1 to 4, inclusive, and I have, therefore, given similar parts corresponding reference numerals.

I preferably produce a tight fit between the outer surface of the mica band 6 and the inner surface of the inner jacket 16 or the inner surface of the body portion 21 as the case may be, but it will be noted that the body portion 21 actually forms a jacket in the same capacity as the jacket 16.

While I have described my invention as taking a particular form, it will be understood that the various parts of my invention may be changed without departing from the

spirit thereof, and hence I do not limit myself to the precise construction set forth, but consider that I am at liberty to make such changes and alterations as fairly come within the scope of the appended claims.

70

Having thus described my invention, what I claim as new and desire to secure by Letters Patent is:

1. An electrode; an insulator for said electrode and having an enlarged portion within its length and providing top and bottom shoulders; an auxiliary band of insulating material surrounding said enlarged portion and having flanges embracing said shoulders; and a metallic jacket incasing the top, bottom and side of said band, substantially as described.

75

2. An electrode; an insulator for said electrode and having an enlarged portion within its length and providing top and bottom shoulders; an auxiliary band of insulating material surrounding said enlarged portion and having flanges embracing said shoulders, said band being made in sections having interlapping portions; and a metallic jacket incasing the top, bottom and side of said band, substantially as described.

80

3. An electrode; an insulator for said electrode and having an enlarged portion within its length and providing top and bottom shoulders; an auxiliary band of insulating material surrounding said enlarged portion and having flanges embracing said shoulders; and a jacket surrounding the side of said band and having inwardly extending portions positioned above and below the flanges of said band, substantially as described.

95

4. An electrode; an insulator for said electrode and having an enlarged portion within its length and providing top and bottom shoulders; an auxiliary band of insulating material surrounding said enlarged portion and having flanges embracing said shoulders; a jacket surrounding the side of said band and having inwardly extending portions positioned above and below the flanges of said band; and washers interposed between said inwardly extending portions of said jacket and the flanges of said band, substantially as described.

100

5. A spark plug of the character described including an electrode; an insulator therefor; an auxiliary insulating band of mica tightly surrounding said electrode insulator; and a metallic jacket tightly inclosing the top, bottom and side of said auxiliary band, substantially as described.

115

In testimony whereof I have signed my name to this specification in the presence of two subscribing witnesses.

WILLIAM S. THOMAS.
